UNITED STATES PATENT OFFICE.

FREDERICK A. OTTOW, OF LOS ANGELES, CALIFORNIA, ASSIGNOR OF ONE-HALF TO
RAYMOND SPALDING, OF LOS ANGELES, CALIFORNIA.

DEVICE FOR CODING AND DECODING TELEPHOTOGRAPHS.

Application filed January 12, 1922. Serial No. 528,873.

To all whom it may concern:

Be it known that I, FREDERICK A. OTTOW, a citizen of the United States, residing at Los Angeles, in the county of Los Angeles 5 and State of California, have invented new and useful Improvements in Devices for Coding and Decoding Telephotographs, of which the following is a specification.

My invention relates to devices for coding and decoding telephotographs, and the purpose of my invention is the provision of a device of this character which greatly simplifies the coding and decoding operations, while at the same time having a capacity 15 greatly exceeding similar devices heretofore proposed.

I will describe two forms of devices embodying my invention and will then point out the novel features thereof in claims.

20 In the accompanying drawings,

Figure 1 is a view showing in front elevation one form of device embodying my invention.

Figure 2 is an end elevation of the device 25 shown in Figure 1, partly in section.

Figure 3 is a fragmentary view partly in section showing the latching means for the table comprised in the device shown in the preceding views.

30 Figure 4 is an enlarged fragmentary view of a portion of the paper securing means comprised in the device.

Figure 5 is a transverse sectional view taken on the line 5-5 of Figure 1.

35 Figure 6 is a fragmentary sectional view of the paper securing means.

Figure 7 is a view showing in end elevation another form of device embodying my invention.

40 Similar reference characters refer to similar parts in each of the several views.

Referring specifically to the drawings 45 my invention in its present embodiment comprises a suitable support or base B upon which are secured spaced standards S formed of metal and preferably filigreed as clearly shown in Figure 2. The journal in the standards is a shaft A, and keyed or otherwise secured to the shaft between the 50 standards are sleeves 15 formed on the ends of filigreed arms 17 which constitute the side portions of a table T. These arms are of substantially triangular formation with

one edge curved in the form of an arc, and these curved edges connected by a curved 55 top 18. The shaft A is adapted to be manually rotated by means of a wheel W and to thereby effect movement of the table T between the standards S. The weight of the table T is counter-balanced by weights 60 19 secured to collars 20 keyed to the shaft A in the manner clearly shown in Figure 5.

The table top 18 is adapted to support a sheet of paper thereon, and this sheet is adapted to be held in fully extended position and contiguous to the top by strips or bars 21 mounted on screws 22 rotatably fitted in the upper and lower edges of the table top, all as clearly shown in Figures 1, 4 and 6. By this arrangement it will be 65 seen that the strips 21 are adjustable toward and away from the top 18 to engage or disengage the ends of a sheet of paper in securing the same in overlying relation to the top. 70

As clearly shown in Figure 1, the standards S are spanned by a straight bar 23 secured at its ends to the standards as at 24 and in overlying relation to the table top 18. A curved bar 25 is secured to one end of the 80 table top 18, and this bar as well as the bar 23 is formed with graduations arranged transversely in the bars as clearly shown. The table T is adapted to be latched in any adjusted position by a spring pressed pin 85 26 mounted on one of the standards S and adapted for engagement within any one of a plurality of notches 27 formed in one of the arms 17. As clearly shown in Figure 3, the notches 27 are formed at intervals corresponding to the graduations of the bar 25 so that when the table T is in latched position, its position with respect to the bar 23 can be accurately determined. 90

In the operation of the device, a sheet of 95 paper containing the photograph to be coded is clamped upon the table top in the manner previously described. By first moving the pin 26 to released position, the table can then be swung by rotation of the wheel W so as to present any desired point of the photograph in close proximity to the bar 23 and by noting the position of this point on the bar 23 and the relative position of the table on the bar 25, the corresponding 100 105 graduations in the two scales are given

thereby allowing of the coding of the photograph, as will be understood by those skilled in the art. The decoding of photograph is obtained by a reversal of this operation.

Referring now to Figure 7 I have here shown another form of device embodying my invention in which the base B is provided with upstanding end portions 28. Secured to these end portions 28 are standards 29 in which a shaft 30 is journaled. This shaft carries a table T' which is of circular form, that is the table is of tubular form and its ends are secured to end portions 31. The table T' is adapted to support the photograph or other subject to be coded, and is provided with a graduated bar 32 adapted to function in the same manner as the bar 25 of the first form of device. The standards 29 also carry a graduated bar 33 similar to the bar 23. One of the standards 29 is provided with a spring pressed pin 34 similar to the pin 26. The table T' operates in the same manner as the table T and in conjunction with the graduated bars 32 and 33 in effecting the coding or decoding of a photograph, it being understood that the photograph is clamped to the circular top of the table. This form of device obviously increases the capacity or size of the photograph to be coded, and at the same time permitting of the photograph to be moved to any desired position with equal facility.

Although I have herein shown and described only two forms of devices embodying my invention, it is to be understood that various changes and modifications may be made herein without departing from the spirit of the invention and the spirit and scope of the appended claims.

What I claim is:

1. A device of the character described comprising a table supported for movement to occupy various positions and having a curved top disposed concentrically of the axis of movement of the table, a scale on the table, and a second scale sustained adjacent the table and disposed at an angle to the first scale.
2. A device of the character described comprising a table supported for movement to occupy various positions and normally urged to one position, means on the table for securing a flexible sheet of material thereto, and coacting graduated bars, one of the bars being secured to the table and the other secured adjacent the table and at right angles to the first bar for the purpose described.
3. A device of the character described comprising a table supported for pivotal movement to occupy various positions, means for latching the table in any position, and coacting graduated bars, one of the bars being secured to the table and the other se-

cured adjacent the table and at right angles to the first bar.

4. A device of the character described comprising a table mounted for pivotal movement to occupy various positions, means for counter-balancing the table to facilitate the movement thereof, means for latching the table in any position comprising a spring pressed pin and notches in the table engageable by said pin, clamping means supported on the table for securing a sheet of flexible material to the table, a graduated bar secured to the table and having the graduations thereof corresponding to said notches, and a second bar sustained adjacent the table and disposed at right angles to the first bar.

5. A device of the character described comprising a table mounted for pivotal movement and having an arcuate shaped top, weights for counter-balancing the table, a graduated bar secured to one end of the table top and extending transversely thereof, means for latching the table in any position comprising a spring pressed pin and notches formed in the table and engageable by said pin, said notches corresponding to the graduations of said bar, and a second graduated bar extending longitudinally of the table and disposed adjacent the same.

6. A device for coding and decoding telephotographs comprising a table having a curved surface, means for attaching a sheet of flexible material to the curved surface, a scale secured to the table, a second scale sustained adjacent the table and in coacting relation with respect to the first scale, and means for manually moving the table whereby said scales are caused to designate any desired point upon the sheet of material carried by the table.

7. A device for coding and decoding telephotographs comprising a table, a measuring device fixed to the table, a second measuring device fixedly sustained in angular relation and juxtaposition with respect to the first measuring device, and means for supporting the table for movement whereby the first measuring device can be moved with relation to the second measuring device to cause the two to designate by measurement any point upon the surface of the table.

8. A device for coding and decoding telephotographs comprising a table supported for movement to occupy various positions, means for latching the table in any position, means for counter-balancing the table, a measuring device fixed to the table, and a second measuring device secured adjacent the table and disposed at an angle with relation to the first measuring device.

9. A device for coding and decoding telephotographs comprising a rigidly supported scale, a flexible sheet supporting member mounted for movement below and trans-

versely of the scale, and a second scale fixed to the member and disposed at an angle to the first scale.

10. A device for coding and decoding tele-
5 photographs, comprising a table supported for movement to occupy various positions, means for latching the table in any position,

a measuring device fixed to the table, and a second measuring device secured adjacent the table and disposed at an angle with relation to the first measuring device. 10

In testimony whereof I have signed my name to this specification.

FREDERICK A. OTTOW.
